Primary Examiner—Alan P. Douglas*Assistant Examiner*—Lavone D. Tabor*Attorney, Agent, or Firm*—Polster, Lieder, Woodruff & Lucchesi**[57] CLAIM**

The ornamental design for a toothbrush with snap-on, snap-off bristle portion, as shown and described.

DESCRIPTION

FIG. 1 is a perspective view of a toothbrush of the present invention;

FIG. 2 is a side elevational view of the toothbrush, the opposite side being a mirror image;

FIG. 3 is a top plan view of the toothbrush;

FIG. 4 is a bottom plan view of the toothbrush;

FIG. 5 is an exploded view of the toothbrush;

FIG. 6 is an end view of the snap-on, snap-off bristle portion of the toothbrush;

FIG. 7 is an end view of the handle portion of the toothbrush in which the bristle end is inserted;

FIG. 8 is an opposite end view of the snap-on, snap-off portion of the toothbrush;

FIG. 9 is a top plan view of the snap-on, snap-off portion of the toothbrush; and,

FIG. 10 is a bottom plan view of the snap-on, snap-off portion of the toothbrush.

The bristled head and handle portions are shown separately in FIGS. 6-10 for clarity of illustration only.
